US00D988342S

(12) **United States Design Patent** (10) Patent No.: **US D988,342 S**
Huntley et al. (45) Date of Patent: **** Jun. 6, 2023**

(54) **DISPLAY SCREEN WITH A GRAPHICAL USER INTERFACE**

(71) Applicant: **Meta Platforms, Inc.**, Menlo Park, CA (US)

(72) Inventors: **Brian Huntley**, San Jose, CA (US); **Aoyu Su**, San Mateo, CA (US)

(73) Assignee: **Meta Platforms, Inc.**, Menlo Park, CA (US)

(**) Term: **15 Years**

(21) Appl. No.: **29/803,409**

(22) Filed: **Aug. 12, 2021**

(51) LOC (14) Cl. **14-04**

(52) U.S. Cl.

USPC **D14/485**

(58) **Field of Classification Search**

USPC **D14/485-95**

CLAIM

The ornamental design for a display screen with a graphical user interface, as shown and described.

DESCRIPTION

The sole FIGURE is a front view of a display screen with a graphical user interface showing the claimed design. The broken lines showing the display screen form no part of the claimed design. The remaining broken lines showing portions of the graphical user interface form no part of the claimed design.

1 Claim, 1 Drawing Sheet
